EDGAR H. BERRY, OF HARPERS FERRY, WEST VIRGINIA

CONTAINER CLOSURE AND PROCESS FOR APPLYING THE SAME

Application filed October 17, 1930. Serial No. 489,292.

This invention relates to a semi-permanent closure for one-time use; the closure, covering a dispensing aperture in the container wall, is applied as one step in the manufacture of the container; the consumer removes and discards the closing element, leaving the dispensing aperture free and uncovered.

The object of this invention is the provision of an economical device, which will close the dispensing aperture in a leak-proof manner, but which is readily removable as above stated.

This invention is illustrated in the accompanying drawing, in which:

15 Figs. 1 and 2 are plan and face views respectively, of a container equipped with a closure of my improved form.

Fig. 3 is a vertical cross section on the center line of Fig. 2.

20 Fig. 4 is a face view of the closing element in a preliminary stage of its production.

Fig. 5 is a side view of the closing element when ready for application.

25 Figs. 6 and 7 are end views of the closing element of Fig. 5.

Figs. 8 and 9 are vertical cross sections corresponding to Fig. 3, but showing successive stages in the application of the closing element.

30 Fig. 10 is a face view of container and closing element, showing the latter in a position corresponding to Fig. 9.

Similar reference characters apply to similar parts in the several figures.

35 The drawing illustrates my invention with particular reference to a cylindrical container, having a side wall a , a permanently attached cap B , and a dispensing aperture c . The latter being in the form of a circular perforation through the side wall a and through the flange d of the cap B .

40 The closing element for the dispensing aperture c (and which I call the "closure strip") is indicated by E in the several figures. In order that this closure strip may be applied in a proper manner, it is in general desirable that the interior of the container be accessible at the time of such application. Thus the closure strip may be applied after one cap B is fastened to the container,

but before the second cap (not shown) is similarly affixed. As will be evident from what follows, after the closure strip has been applied in the contemplated manner, this strip so seals the dispensing aperture c that 55 the container becomes a virtually non-perforate unit, open at one end until the second cap is affixed, and can be correspondingly handled for filling and final sealing.

45 The dispensing aperture c is conveniently made of circular form. The closure strip E may be of light cardboard, or of heavy paper, or folded from several plies of lighter paper, as may be most convenient. To simplify the drawing, I show this strip as presenting only 60 a single ply, but I find that the general principle of the closure applies equally well to a closure strip which is folded longitudinally to present several plies of appropriate thickness.

55 Referring more particularly to the single-ply closure strip above mentioned, this may be cut from the flat material in the tapered form shown in Fig. 4. It is then curled transversely (Figs. 6 and 7) and also longitudinally as shown in Fig. 5. I find that 70 this double curling is readily effected, as for example, by drawing the strip over a mandrel through a conical die. The curvature presented by the transverse curl (Figs. 6 and 7) is preferably less sharp than the curvature presented by the perimeter of the dispensing aperture c , so that when the closure strip is threaded through this aperture as 75 hereinafter referred to, the strip will tend to hug the edge of the aperture.

80 The closure strip E , curled as above, is threaded through the dispensing aperture c (see Fig. 8) the large end of the strip being 85 inside the container. I then press the inner or tail end of this closure strip into the position shown in Fig. 9, as for example by means of co-acting die blocks F and G . I also bend the outer or head end of the strip sharply at h (over the edge of the container cap B) into the position shown by dot-and-dash lines in Fig. 9, this operation being 90 conveniently performed by the thumb and fingers of the operator.

95 In threading the closure strip through the

dispensing aperture as above described, I pull this strip through until its gradually enlarging taper engages the edge of the dispensing aperture *c* with a firm wedging action (see Fig. 10). This calls for applying a moderate but appreciable tension to the strip, and I take care to maintain substantially the same tension when giving this strip the sharp bend at *h* already mentioned. Still 10 maintaining a similar tension, I bind the head end *i* of the closure strip to the container in any convenient manner, say for example, by the gummed seal or sticker *J* Figs. 1, 2, 3. In this way, the closure strip 15 is firmly wedged in the dispensing aperture *c* against any tendency to slip forward (outward), and is tensely bound (by the binding means *J*) against the possibility of slipping backward (inward). This condition is 20 clearly indicated in Fig. 2.

The closure strip, thus wedged against the sides of the dispensing aperture, conforms itself to the lower semi-circumference of this aperture under the action or pressure of the 25 die blocks *F* and *G* (Fig. 9), and conforms itself to the upper semi-circumference as a result of the bending under tension at *h* (Figs. 9 and 3); but at the same time, the previously formed curl tends to persist in 30 that small portion of the closure strip *E* which actually lies within the dispensing aperture *c*, (or between the points *h* and *p*, Fig. 9).

When the die blocks *F* and *G* are released, 35 the slight though appreciable resiliency of the closure strip causes the tail end of the latter to bulge out slightly as indicated at *n* Fig. 3, although the extreme end *m* (of the closure strip) tends to remain close to 40 the container wall as shown; but releasing the said die blocks does not result in any springing-away of the closure strip from its engagement with the lower semi-circumference of the dispensing aperture, because any 45 tendency toward such springing-away is counterbalanced by the already mentioned tendency of the curl to persist in that portion of the closure strip which lies within the dispensing aperture. In other words, 50 by the several successive steps which have been described, the closure strip is deformed from an originally flat blank, and is embossed or molded into close engagement with the entire perimeter of the dispensing aperture.

My use of the term "embossed" is not to be understood as implying that either of the die blocks has to be provided with an embossing protuberance or hollow. One 60 reason for the security of my closure is found in the fact that the embossing or molding effect is largely controlled by those portions of the container wall adjacent to the dispensing aperture itself, and die blocks with 65 smooth cylindrical surfaces (acting on the

curled and wedgedly confined closure strip) serve to apply the necessary pressure. When dealing with a small container and a light closure strip, I may even make the die block *F* a stationary horn (similar to the horn of an anvil) and apply manual pressure to the external block *G*.

While the embossing or molding effect is important in attaining a tight closure, yet in view of the relatively slight thickness of the materials dealt with, the actual amount of such embossing or molding is not very great, and the force which has to be applied is correspondingly moderate.

Referring further to the security of the closure attained, it will be noted that insofar as there may be any tendency for the closure strip to revert to its original flat shape, this will tend to increase (rather than diminish) the firmness with which this strip is confined by the edge of the dispensing aperture.

In the original production of the closure strip *E*, the stiffness and number of plies of its material, its width and taper, and its transverse curl, must of course be properly proportioned with respect to each other, with respect to the size of the dispensing aperture, and with respect to whether the container wall is flat or moderately curved or sharply curved. My drawing shows a fair average case, in which the greatest width of the closure strip is somewhat greater than one and one half times the diameter of the dispensing aperture, and the transverse curl shown in Fig. 7 is nearly a semi-circle.

The security of my closure, sufficient to prevent leakage of even very fine powder, is more easily understood by an inspection of the actual article than from any written description. If desired, a small amount of sealing material (paraffin or the like) may be applied to the exposed edges *k* and *l* (of aperture and strip respectively), see Fig. 2. This however, is merely a supplementary precaution, not a direct necessity in forming 100 a secure closure.

As already mentioned, after the closure strip has been applied and secured, the container (still having one end open) may be filled; the open end may then be capped and sealed in any convenient manner. The purchaser desiring to dispense the contents, breaks the seal *J* (or other equivalent fastening), and pulls the closure strip *E* out of the dispensing aperture, the edges of the strip curling sufficiently to permit of such withdrawal without tearing either the strip or the edges of the dispensing aperture. It will be noted that such final removal of the closure strip leaves the dispensing aperture with smooth edges, and free from such remnants as might adhere after the removal of a seal pasted over the dispensing aperture itself.

I claim:—

1. A closure for a dispensing aperture in the wall of a container, the said closure comprising a closure strip and means for binding this strip to an external surface of the container, the strip presenting a taper adapted to enter into wedged engagement with the edge of the dispensing aperture, and the large end of the taper being inside the container.

10 2. A closure for a dispensing aperture in the wall of a container, the said closure comprising a closure strip and means for binding this strip to an external surface of the container, the strip presenting a taper and a transverse curl, the taper and the transversely curled face of the strip being adapted to enter into wedged engagement with the edge of the dispensing aperture, and the 15 large end of the taper being inside the container.

20 3. A closure for a dispensing aperture in the wall of a container, the said closure comprising a closure strip and means for binding this strip to an external surface of the container, the strip presenting a taper and a longitudinal curl, the taper and the longitudinally curled face of the strip being adapted to enter into wedged engagement 25 with the edge of the dispensing aperture, and the large end of the taper being inside the container.

30 4. A closure for a dispensing aperture in the wall of a container, the said closure comprising a closure strip and means for binding this strip to an external surface of the container, the strip presenting a taper, a transverse curl, and a longitudinal curl, the taper and the doubly curled face of the strip 35 being adapted to enter into wedged engagement with the edge of the dispensing aperture, and the large end of the taper being inside the container.

40 5. The process of effecting a semi-permanent container closure of the herein described nature, by threading a curled tapered closure strip through the aperture to be closed, making a localized engagement between the strip and the edge of the aperture under tension applied to the strip, extending such engagement around the perimeter of the aperture by internal and external pressure, and locking the strip in such engagement by 45 binding the strip to the container.

50 55 EDGAR H. BERRY.
